UNITED STATES PATENT OFFICE

166,397

CHAIR

Ray Komai, New York, N. Y., assignor to J. G. Furniture Co., Inc., Brooklyn, N. Y., a corporation of New York

Application February 23, 1950, Serial No. 8,074

Term of patent 14 years

(Cl. D15—1)

To all whom it may concern:

Be it known that I, Ray Komai, a citizen of the United States, residing in the city and county of New York and the State of New York, have invented a new, original, and ornamental Design for a Chair, of which the following is a specification, reference being had to the accompanying drawing, forming part thereof.

Fig. 1 is a front perspective view of a chair showing my new design; and Fig. 2 is a rear perspective view thereof.

I claim:

The ornamental design for a chair, as shown.

RAY KOMAI.
